CLAIM

The ornamental design for a sample collection device, as shown and described.

DESCRIPTION

FIG. 1 is front isometric view showing the new design for a sample collection device;

FIG. 2 is a rear isometric view thereof;

FIG. 3 is a top plan view thereof;

FIG. 4 is a bottom plan view thereof;

FIG. 5 is a left side view thereof;

FIG. 6 is a right side view thereof;

FIG. 7 is a rear view thereof; and,

FIG. 8 is a front view thereof.

The broken lines are for the purpose of illustrating portions of the article and form no part of the claim.

1 Claim, 5 Drawing Sheets
